UNITED STATES PATENT OFFICE.

FRITZ JACOBSON, OF BROOKLYN, NEW YORK.

VAPORIZER.

SPECIFICATION forming part of Letters Patent No. 691,772, dated January 28, 1902.

Application filed April 16, 1901. Serial No. 55,943. (No model.)

To all whom it may concern:

Be it known that I, FRITZ JACOBSON, residing in New York, borough of Brooklyn, county of Kings, State of New York, have invented 5 certain new and useful Improvements in Vaporizers; and I do hereby declare that the following is a full and clear description thereof.

My invention relates to vaporizers or evaporators.

10 The improvements constitute a steam vaporizing device. It is more particularly designed for the purpose of evaporating or evaporizing medical compounds in order to distil medicine for the purpose of impregnating the 15 air of a room or apartment and at the same time prevent the escape of any watery vapor into the room.

For these purposes my invention consists 20 in the following construction and combinations of parts, the details of which will be first described and the patentable features then set forth and claimed.

25 Figure 1 represents a side elevation of a device embodying my invention. Fig. 2 represents a central vertical section of the same. Fig. 3 is a top plan view.

In the drawings, 1 represents the combustion-chamber, which may be of any suitable 30 dimensions or configuration. This chamber is provided with means for maintaining heat beneath the boiler, such as a lamp 2. Suitable entrances, as perforations 3, may be provided to introduce air to the combustion-chamber. The productions of combustion 35 may escape through the annular orifice 4, between the edges of the chamber 1 and the boiler.

40 4 is the usual door of the combustion-chamber, having an opening covered with a transparent 5.

45 6 is a water-boiler, preferably supported upon lugs 7 above the combustion-chamber. This boiler is entirely closed to the escape of vapor or steam therefrom except through the safety-valve 7 under undue pressure. Boiler 6 is provided with an opening 8, closed by a cap 9, for the purpose of filling the same with water or other heating media when desired.

50 10 represents a pair of condensers, preferably supported above the boiler at a suitable distance, as shown. Suitable tubes 11 connect the boiler-space with the condensers.

One of the condensers may be provided with a safety-valve 7, which can be adjustably set to blow off at any desired pressure. Other 55 than through the cap 9 and safety-valve 7 there is no communication with the boiler or condensers and the outer air.

12 is a thermometer-tube supported by the upper wall of the boiler 6. This tube enters 60 the boiler and passes into the interior of the same, but has no connection with said interior. The tube 12 is adapted to contain an ordinary thermometer, with the thermometer-bulb at the lower end. The tube 12 is open 65 at one side, whereby the scale of the thermometer may be read within the range of certain degrees essential for the proper operation of this vaporizer.

13 is a depressed annular receptacle formed 70 in the top of the boiler and projecting into the interior thereof. This depression is adapted to hold a basin or receptacle 14, within which the medicine is placed for distillation or vaporization. The depression 13 is deep 75 enough to permit the vessel 14 to be surrounded upon its sides and bottom with effective heating-surfaces of the boiler.

In operation the boiler 6 is filled through the opening 8 to any proper degree with water. 80 The medicine to be vaporized is placed into the basin 14. The lamp 2 is lighted. The vapor generated by the heat of the lamp collects in the upper part of the boiler and in the tubes 11 and condensers 10. No escape of 85 steam is permitted unless the pressure generated within the boiler and condenser exceeds the amount for which the safety-valve is set, when the latter blows off.

In the distillation of medicine for the purpose of impregnating the atmosphere it is essential that the heat generated does not exceed 220° Fahrenheit. Above that temperature, generally speaking, destructive vaporization takes place, which destroys the curative properties of any medicine used for the purpose of air medication. The proper temperature at which effective vaporization of vaporized medical compounds should range 90 is from 200° to 220°. The dry vaporization of 100 medicine, where the heat is applied directly thereto without the intervention of a transmitting heat medium, like water, is also destructive of the properties of the medicine,

the inhaling effects of which, in pulmonary diseases especially, are suffocating rather than curative.

- With the use of my vaporizer I am enabled
- 5 to apply heat in a beneficial manner by the employment of a fluid agency and at the same time prevent evaporated particles of that agency escaping into the room. In the treatment of consumption it is especially de-
  - 10 sirable to keep the atmosphere free from all moisture. This result is obtained through the action of the condensers, which condense the vapor and return it to the boiler to be used over again.
  - 15 The thermometer-tube, with a thermometer, enables the proper temperature to be maintained, whereby the temperature of the steam generated in the boiler is kept below the point of destructive distillation of the medi-
  - 20 cal properties of the medicine and the escape of steam into the room through the blow-off prevented.
  - 25 If desired, the medicine could be deposited directly into the depressed annular portion
  - 13 of the boiler; but I prefer a separate utensil 14 for that purpose, in order that the medicine may be more readily prepared and the vessel more easily kept clean. Instead of a lamp I may use any other heating agency,
  - 30 such as gas, electricity, coal-combustion, &c.

The shape of the combustion-chamber of the boiler and the condensers may be varied, as will be obvious, without departing from the spirit of my invention.

My invention is distinguished from condensing-engines and boilers in the fact that the whole device is portable, the combustion-chamber supporting the boiler and condenser being a self-contained article of manufacture.

What I claim as new, and desire to secure 40 by Letters Patent, is—

In a portable vaporizer apparatus for medicine, the combination of a combustion-chamber, a water-chamber above the combustion-chamber having a depressed portion in the 45 top thereof, said depressed portion having a fluid-tight connection with the water-chamber, a sealed condenser above and separate from the water-chamber, a pipe connection between the condenser and the water-chamber, 50 a thermometer-tube projecting into the water-chamber and a safety-valve, the whole apparatus being fluid-tight whereby steam is prevented from escaping into the room.

In testimony whereof I have affixed my signature in the presence of two witnesses.

FRITZ JACOBSON.
